FOREIGN PATENT DOCUMENTS

JP 1474740 S 7/2013

Primary Examiner — Selina Sikder

(74) Attorney, Agent, or Firm — Cermak Nakajima & McGowan LLP; Tomoko Nakajima

(57) **CLAIM**

The ornamental design for a tray for a card connector, as shown.

DESCRIPTION

FIG. 1 is a front elevational view of a tray for a card connector showing my new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a bottom plan view thereof.

FIG. 7 is a front and top perspective view thereof;

FIG. 8 is a rear and top perspective view thereof;

FIG. 9 is a front and bottom perspective view thereof; and

FIG. 10 is a rear and bottom perspective view thereof; and, FIG. 11 is a cross sectional view thereof taken along the line A-A shown in FIG. 2.
